[57] **CLAIM**

The ornamental design for a transmission detent cable connector, substantially as shown.

DESCRIPTION

FIG. 1 is a perspective view of one side of a transmission detent cable connector, showing my new design; FIG. 2 is a perspective view of the opposite side thereof;

FIG. 3 is a longitudinal cross-sectional view taken through the center thereof;

FIG. 4 is an elevation view showing one end thereof; and

FIG. 5 is an elevation view showing the opposite end thereof.

FIG-1
